UNITED STATES PATENT OFFICE.

THOMAS JAMES PUPPLETT, OF MANCHESTER, ENGLAND.

INTERNAL-COMBUSTION TURBINE.

1,423,453.

Specification of Letters Patent. Patented July 18, 1922.

Application filed December 9, 1921. Serial No. 521,245.

To all whom it may concern:

Be it known that I, THOMAS JAMES PUPPLETT, a subject of the King of Great Britain and Ireland, and resident of 172 Oxford 5 Road, Manchester, in the county of Lancaster, England, have invented certain new and useful Improvements Relating to Internal-Combustion Turbines, of which the following is a specification.

10 This invention relates to internal combustion turbines of the type in which the combustible charge after ignition is directed on to a vane wheel and comprises the improved combination and arrangement of parts for 15 compressing the combustible charge, transferring the same to the combustion space and for permitting the same to impinge upon the vane wheel.

The invention comprises the combination 20 with a vane wheel having a fixed sleeve or ring-like element therearound with guide passages therethrough, of a movable sleeve or ring with guide passages therethrough around the fixed sleeve or ring, an annular 25 combustion chamber around the said movable sleeve, and means actuated by the pressure of the combustion in said annular chamber for moving the said movable sleeve or ring relatively to the fixed ring for bringing 30 the passages in the two rings out of or into alignment with one another.

The invention further comprises the combination with the vane wheel having the fixed and movable sleeves therearound, and 35 with the combustion chamber surrounding the sleeves, of an annular pumping space with a ring like piston therein for compressing the combustible charge into said space.

The invention further comprises the details of construction and arrangement hereinafter described.

Referring to the four accompanying sheets of explanatory drawings:—

Figure 1 is a sectional elevation through 45 an internal combustible turbine constructed in one convenient form in accordance with my invention.

Figure 2 is a sectional end elevation on the line 2—2 of Figure 1.

50 Figure 3 is a sectional end elevation on the line 3—3 of Figure 1.

Figure 4 is an elevation with the upper part in section on the line 4—4 of Figure 3.

55 Figure 5 is a sectional plan view on the line 5—5 of Figure 3.

The same reference letters in the different views indicate the same parts.

In accordance with my invention, the vane wheel *a* is surrounded by a fixed sleeve or ring-like element *b* having guiding passages *b*¹ therethrough for directing the products of combustion on to the vane wheel. There is also arranged a second sleeve or ring *c* around the fixed ring, the second sleeve having guide passages *c*¹ therethrough which, by the movement of the sleeve *c* can be brought into and moved out of alignment with the passages *b*¹ through the fixed ring *b*. The combustion space *d* of the turbine is disposed around the movable sleeve *c* and piston-like parts *e* connected to said sleeve *c*, hereinafter termed the sleeve valve, serve when the pressure in said combustion space *d* exceeds a predetermined amount, to move the said sleeve valve *c* and open the passages 75 whereby the products of combustion are allowed to issue into or impinge upon the vane wheel *a*.

One of the pistons *e* is adapted to be operated from a cam shaft *g* which can move the sleeve valve *c* positively to bring the ports *c*¹ and *b*¹ into alignment and can also move said sleeve valve to put the said ports out of alignment through the medium of the spring *h*. The positive means for positively actuating one of the pistons *e* preferably 80 consists of an element which is slidable through the end of the cylindrical chamber and operatively associated with the spring *h* the opposite end of the cylinder being pivotally connected with a pitman which in turn is operated by the cam shaft *g* as indicated in Fig. 2.

In order to insure of the proper admission of the charge in the combustion chambers *d*, two spark plugs are employed being positioned through the walls of the chambers and preferably opposite each other and on opposite sides of the restricted portions of these chambers adjacent the bearings of 100 the piston rods *p*.

In order to exhaust the dispensed products of combustion exhaust passages *j* are provided. These passages are in the form of tubes preferably in threaded engagement with the inner fixed ring *b* and the outer wall of the chamber. In this connection it is to be observed that the passages or tubes serve as a means for fixing the ring *b*.

The fuel charge is drawn past the slide 110

valves *k* (Figure 4) and compressed in annular spaces *m* around the turbine shaft *n*, and preferably of approximately the same cross sectional dimensions as the combustion space. The pistons *o* are of annular ring-like form and have packing rings thereon. There are preferably two piston rods *p* at diametrically opposite points, the said rods being reciprocated by suitable crank pins *q*, connecting rods *r* and a cross head *s* from the turbine power shaft *n*.

In the illustrated arrangement, I have provided three vane wheels *a* upon the one power shaft, and I provide two pump cylinders and pistons, the two end combustion chambers being supplied with a fuel charge by the respective pumps, whilst the centre combustion chamber is supplied by both pumps, which are double acting. It will be seen that with this arrangement, the centre turbine wheel receives twice as many charges as each end turbine wheel.

With the arrangement of parts before described, each pump draws in a fuel charge through a carburettor and the slide valve *k* and compresses it into a combustion chamber *d* through a suitable valve *u* (see Figure 5) which may be a slide valve operated by the cam shaft *g*, each valve closing when the pump completes its compression stroke, and the charge being thereafter ignited in the combustion chamber *d* by an electric spark in the usual manner. The transfer port to the combustion space is shown at *v*. The pressure of combustion in the combustion chamber acting upon the pistons *e* connected to the sleeve valve *c* opens the guide ports by which the products of combustion are directed on to the vane wheel *a*. The sleeve valves may close automatically under the pressure of the spring *h* when the pressure in the combustion space falls or the said valves will be closed by the cam actuated mechanism before described just prior to the commencement of the charging or compression stroke of the pump. A similar series of operations occurs at each vane wheel.

The casing adjacent the vane wheels *a* and the charging pumps *o* may have water jackets therein.

Passages or ports *w* may be provided to prevent the accumulation of pressure in the spaces *x* between the vane wheel casings.

I do not limit myself to any particular details of my improved internal combustion turbine, but may modify the same to suit any particular services or requirements.

I claim:—

1. In internal combustion turbines, the combination with a vane wheel, of a cylindrical ring-like element arranged in spaced relation peripherally of the wheel, a sleeve valve disposed about and contacting with the ring-like element, an annular combustion

chamber arranged in spaced relation about the periphery of the sleeve valve, means for controlling the admission of compressed gases into the combustion chamber, means for igniting the gases, the ring-like element and sleeve having guide passages therethrough for directing the products of combustion against the vane wheel and spring controlled means normally keeping said passages out of alignment actuated by the pressure of combustion in said annular chamber for moving the sleeve valve to bring the passages in the ring and sleeve valve into alignment with one another and means for exhausting the products of combustion.

2. In internal combustion turbines as claimed in claim 1 the provision of positive means for operating the sleeve valve in combination with the spring controlled pressure operated means.

3. In internal combustion turbines as claimed in claim 1 wherein the spring controlled pressure operable means includes cylindrical chambers communicating with the annular chamber, spring controlled pressure operable piston heads in the cylinders and a link connection between the piston heads and the movable sleeve valve.

4. In internal combustion turbines in combination with a vane wheel, of a fixed cylindrical ring-like element arranged peripherally thereof and provided with guide passages therethrough, a sleeve valve disposed around and contacting with the ring-like element and also provided with guide passages therethrough, an annular combustion chamber arranged in spaced relation about the periphery of the sleeve valve and combined spring controlled pressure operated and positively operated means for moving the sleeve valve to effect the alignment and non-alignment of the passages through the ring-like element and sleeve valve, said means including a cylindrical chamber communicating with the annular chamber, a piston head operating in the cylindrical chamber, a link connection between the piston head and the sleeve valve, a spring acting to hold the piston head toward the inner end of the cylindrical chamber, an element slidably through the cylindrical chamber and operatively associated with the spring, a pitman rod operatively connected with said element and a cam shaft with which the pitman rod is associated.

5. In internal combustion turbines, in combination, a plurality of vane wheels, a fixed cylindrical ring arranged peripherally about each vane wheel and having passages therethrough, a sleeve valve disposed about each fixed ring and also having passages therethrough, an annular combustion chamber arranged in spaced relation about the periphery of each sleeve valve, a plurality of annular pumping spaces laterally of

- and between the annular combustion chambers, a ring-like piston in each pumping space for compressing combustible gases, means for controlling the admission of the 5 gases into the combustion chambers, means for igniting the gases in each annular combustion chamber, spring controlled pressure operable means in each chamber for bringing the passages in the ring in alignment 10 with the passages in the sleeve so that the products of combustion will be directed on the vane wheel, said spring means subsequently acting to bring said passages out of alignment and means for exhausting the 15 products of combustion.
6. In internal combustion turbines in combination, a main shaft, a plurality of vane wheels in spaced relation thereon, a fixed cylindrical ring arranged peripherally about 20 each vane wheel and having passages therethrough, a sleeve valve disposed about each ring-like element and having passages therethrough, an annular combustion chamber arranged in spaced relation about the periphery of each sleeve valve, a plurality 25 of annular pumping spaces laterally of and between the annular combustion chambers, valve means operatively connected with the main shaft for controlling the admission of gases to the spaces, a ring-like piston operating in each pumping space for compressing the gas charges therein, common means connecting the ring-like pistons with the main shaft, valve controlled means operatively connected with the main 30 shaft for controlling the passage of the compressible gases into the annular combustion chambers, means for igniting the gases, spring controlled means in each chamber operable by the pressure of the gases for 35 bringing the passages in the ring and sleeve into alignment so that the products of combustion will be directed on the vane wheel, said spring controlled means subsequently 40 acting to move the passages out of alignment, and means for exhausting the products of combustion.
7. Internal combustion turbines as claimed in claim 1 wherein the exhaust means includes conduits between the chamber and 45 the inner ring to hold the latter in fixed relation with respect to the vane wheel in addition to accomplishing its exhausting purposes.
- In testimony whereof I have signed my 50 name to this specification.

THOMAS JAMES PUPPLETT.
